CLAUDE NOLAN AND WILLIAM J. RAY, OF JACKSONVILLE, FLORIDA

STARTER MECHANISM LOCK

Application filed December 3, 1928. Serial No. 323,529.

This invention relates to new and useful improvements in starting devices, and particularly to starting devices for automobiles.

One object of the invention is to provide a novel and improved means for effectively preventing operation of the starter mechanism, while the engine is running.

In devices of this character, heretofore, the oil system of the automobile was involved, 10 the oil pressure, when the engine was running, serving to operate a locking means which prevented operation of the starter. This was, however, found to be very uncertain, and ineffective, for the reason that, 15 when the weather was cold, the oil became very thick and sluggish, with the result that after having only too quickly built up sufficient pressure to render the lock effective, it was found that the oil was too thick to permit 20 the required quick release of the lock, and therefore prevented the desired repeated attempts to start the engine. When, however, the oil was thin, the system drained too quickly to permit the proper rapid building 25 up of pressure to permit the proper operation of the lock. From the above experience, the present applicant promptly discarded the use of oil, and substituted the present device.

Another object is to provide a novel and 30 efficient means for preventing operation of the starting motor, while the engine is running, such means being controlled by the vacuum from the intake manifold.

Another object is to provide a device of 35 this character which is readily applicable to different kinds of automobiles, without the necessity of modifications to the various parts thereof.

A further object is to provide a locking 40 means for the operating part of the starter mechanism whereby all danger of injury or breakage to such parts will be effectively prevented.

Other objects and advantages will be apparent from the following description when taken in connection with the accompanying drawings.

In the drawings:

Figure 1 is a side elevation of a starter mechanism, showing the invention, only such

parts of an automobile being shown as are directly connected therewith.

Figure 2 is a horizontal sectional view therethrough.

Figure 3 is a vertical sectional view on the line 3—3 of Figure 2.

Figure 4 is a fragmentary plan view showing the cam and lock.

Figure 5 is a plan view showing the application of the invention to another form of 60 starting mechanism.

Figure 6 is a sectional view through the form of starter shown in Figure 5.

Figure 7 is a plan view of another form of 65 the device.

Figure 8 is a vertical sectional view on the line 8—8 of Figure 7.

Referring particularly to the accompanying drawings, and especially to Figures 1 to 4, 10 represents a portion of an engine of an 70 automobile, and 11 the intake manifold thereof, in connection with which the present invention is especially adapted for use. Secured to the engine block is a plate 12, having the transversely aligned bearings 13, on 75 one end, in which is rotatably supported the shaft 14. On one end of the shaft is secured the vertically extending pedal lever 15, while an arm 16 is secured on the other end of the shaft, the former being adapted for the use 80 of the foot of the operator, while the latter serves to operate a switch (not shown) which controls the current which operates the starting motor (not shown). The before-mentioned bearings 13 are spaced apart, as 85 shown, and keyed on the shaft 14, between said bearings, is a forked cam member 17, to which more particular reference will be made later herein. Formed on the other end of the plate 12, and extending longitudinally thereof, is a cylinder 18, within which moves the piston 19, the other end of the stem 20 of which is slidably disposed through an opening 21 in an end of the cylinder. 90 Loosely secured on the projecting end of the stem 20 is a head 22, which is adapted to move into and out of the path of the before-mentioned cam 17. The other end of the cylinder is closed by a cap 23, and secured 95 within the cap is a nipple, to which is se-

100

cured one end of the conduit 24, which has its other end secured to the intake manifold 11, to permit the vacuum therefrom to act upon the piston 19, as will be more clearly explained later herein. Within the nipple-carried end of the cylinder is a coil spring 25, which bears against the adjacent end of the piston and the said cap, whereby to normally and resiliently maintain the piston at the other end of the cylinder.

It will be understood that, when the engine is at rest, there is no vacuum action in the intake manifold 11, therefore the piston 19 is urged by the spring 25, to the other end of the cylinder 18, thereby permitting the rocking of the shaft, by means of the pedal 15, so that the forked end of the cam 17 will straddle the stem of the piston, and said cam move down into contact with the plate 12, and also permitting the arm 16 to perform its function of closing the electric circuit to the starter motor, as is well understood. When the engine is running, the vacuum created in the manifold 11 will draw the piston 19 forward, against the action of the spring 25, thereby moving the head 22 into a position where the forked end of the cam 17 will engage on the upper face thereof, and be prevented from further rotation, with the result that the operator cannot move the pedal lever 15 far enough to permit the arm 16 to act upon the circuit closer of the starter switch. As long as the engine is running, the vacuum created in the manifold will act upon the piston to hold the same in such position that the shaft 14 cannot be rocked. When the engine is stopped, the vacuum ceases to act upon the piston, when the head 22 is withdrawn, by the action of the spring 25, out of the path of the cam, thus permitting the pedal to be moved, and the forked end of the cam to straddle the stem of the piston, and the starting operation be properly performed.

Referring particularly to Figures 5 and 6, there is shown an adaptaton of the device to another form of starter device. In this device there is shown the ordinary spring urged starter button 26, said button being operable within and through a housing 27, within which is arranged the usual switch. On this housing is mounted a plate 29, which supports a cylinder 30, within which moves a piston (not shown), having the stem 32 movable through an end thereof, said cylinder having its other end connected with an intake manifold (not shown), by means of the conduit 33. To the outer end of the stem 32 is connected a transversely extending arm 34 which is arranged to be moved into and out of the path of the button 26, for the purpose of preventing operation of the button while the engine is in motion. The housing also carries a stop member 35, against which the arm 34 is adapted to engage, in its outer-

most position, when released from the path of the button.

In Figures 7 and 8 there is shown a further form of the device, for adaptation to another type of starter mechanism. In this form of the device there is provided a base plate 36, on which is mounted the cylinder 37, in which is disposed a spring pressed piston (not shown), said piston having the end of the stem 39 provided with a plate 40 movable in the guides 41, and in said plate there is formed an elongated wedge opening 42. In the plate 36, beneath the opening of the plate 40, there is formed an opening 43 through which passes the operating stem 44 of the starter mechanism. Formed on this stem is an integral collar 45, which, when the plate 40 is withdrawn by the piston 39, will dispose the smaller portion of the opening 42 in the path of the collar of the stem, thereby causing the collar to engage the portions of said plate, at the sides of said smaller part of the opening, thereby preventing downward movement of the stem, and the operation of the starting motor.

In the cap carrying end of each of the cylinders there is disposed a centrally apertured washer 46, against which the piston tightly engages. As it moves toward said end of the cylinder, whereby to cause the same to properly expand within the cap, so that all danger of loss of vacuum is prevented.

From the foregoing it will readily be seen that, when the engine is at rest, the detent, or stop member, will be out of the path of the operating element of the starter mechanism, with the result that the starting motor can be readily operated. However, after the engine is in motion, and vacuum created in the intake manifold, the piston will be drawn to place the stop member directly in the path of the operating element, with the result that the operation of the starting motor is rendered impossible, and all danger of injury to the motor or fly-wheel gears obviated.

What is claimed is:

1. In a locking device for the starting mechanism of an automobile, a rock shaft, means for rocking the shaft, a switch operating arm on the shaft, a forked arm on the shaft, and a block operable by the suction of an automobile engine into position to be engaged by the furcations of said arm and thereby prevent rocking of the shaft, and means for operating said block into a position out of the path of said furcations, to permit rocking of the shaft.

2. In a locking device for the starting mechanism of an automobile, a rock shaft, means for rocking the shaft, a switch operating arm on the shaft, a forked arm on the shaft, a vacuum cylinder operatively connected with the vacuum producing means of an engine, and a piston in the cylinder having a stem provided with a terminal block mov-

able into position to be engaged by the furcations of the arm, at times, to prevent rotation of the shaft and operation of the switch, and into position to permit the furcations to straddle said stem, at times, whereby to permit the shaft to be rocked.

3. In a locking device for the starting mechanism of an automobile, a rock shaft, means for rocking the shaft, an arm on the shaft for rocking movement therewith, a movable stop means adapted for engagement by said arm, at times, means for urging said stop means normally into a position out of the path of said arm, whereby to permit rocking of said shaft in one direction and to be engaged and held by said arm against movement out of said position, when the shaft is thus rocked, and means for moving said stop means into the path of said arm, when the shaft is rocked in the other direction, whereby to prevent subsequent rocking of said shaft in the first-named direction.

4. In a locking device for the starting mechanism of the engine of an automobile, a rock shaft, means for rocking the shaft, an arcuate arm on the shaft, a movable stop means, means normally holding said stop means in a position adjacent the shaft and out of the path of said arm, whereby to permit rocking of the shaft in one direction and to position said arm in the path of said stop means, and means operable by the engine of the automobile for moving said stop means into the path of said arm, upon rocking the shaft in the other direction, whereby to prevent subsequent rocking of the shaft in the first direction while the engine is running.

5. In a locking device for the starting mechanism of an automobile, a rock shaft, means for rocking the shaft in one direction, an arcuate arm on the shaft, a movable stop member, resilient means normally urging said stop member into a position between said shaft and the path of said arm, to permit rocking of the shaft in one direction and the movement of said arm into the path of said stop member, whereby to engage and hold said stop member from movement in the opposite direction, said stop member being operable in the opposite direction by the suction of the engine of an automobile into the path of said arm, upon rocking said shaft in said opposite direction, whereby to prevent subsequent rocking of the shaft in the first-named direction after having been rocked into normal position.

6. The combination with a rock shaft having a radial arcuate arm, of a stop, resilient means for urging said stop in one direction, vacuum means for operating the stop in the opposite direction, said stop when in resiliently urged position permitting rocking of the shaft in one direction and the engagement of one of its faces by said arm to hold the stop from movement in the opposite di-

rection under vacuum influence, said shaft when rocked in said opposite direction releasing said stop, whereby said stop will be moved into the path of said arm to present another of its faces for engagement thereby to prevent subsequent rocking of the shaft in the first-named direction.

7. The combination with a rock shaft having a radial arcuate arm movable in an arcuate path, of a stop, resilient means urging the stop in one direction whereby to lie out of the arcuate path of said arm but to be engaged and held by said arm, upon rocking said shaft in one direction, and vacuum means for moving said stop in the opposite direction to lie in said arcuate path of the arm, upon rocking of said shaft in the opposite direction, whereby to prevent subsequent rocking of said shaft in the first-named direction.

In testimony whereof, we affix our signatures.
